UNITED STATES PATENT OFFICE.

LOUIS GODDU, OF WINCHESTER, MASSACHUSETTS, ASSIGNOR, BY MESNE ASSIGNMENTS, TO GODDU SEWING MACHINE COMPANY, A CORPORATION OF MAINE.

SEWING-MACHINE.

1,106,800.

Specification of Letters Patent. Patented Aug. 11, 1914.

Application filed May 20, 1895. Serial No. 549,898.

To all whom it may concern:

Be it known that I, Louis Goddu, of Winchester, county of Middlesex, State of Massachusetts, have invented an Improvement 5 in Sewing-Machines, of which the following description, in connection with the accompanying drawings, is a specification, like letters on the drawings representing like parts.

10 This invention has for its object the production of a novel sewing machine more especially designed for sewing leather in the production of boots and shoes, with a strong serviceable locked stitch composed of 15 two continuous threads.

The stitch is produced by means of a hooked needle which enters a hole previously made in the leather from preferably the outer face of the outer sole or a channel 20 therein, the needle having deposited in its hook one strand of a loop-like portion of needle thread already drawn off from the thread supply by a looper and yet held thereby, the looper giving up the thread 25 held by it to the needle as the latter draws the loop of needle thread through the leather. The loop of needle thread having been drawn through the leather, a thread-catcher enters the said loop near the end of 30 the needle and engages beyond it a second thread extended from a thread guide,—preferably stationary,—to the leather, and having engaged said thread the catcher will preferably be raised a little to enable a portion 35 thereof forming a cast-off to meet the loop of thread held by the needle, and thus cast off the loop of needle thread from the hook of the needle, the needle during this operation being preferably lowered for a 40 short distance, the loop of needle thread being cast off just before or as the thread-catcher then in engagement with the second thread begins to descend in the open loop of needle thread, the thread-catcher de-

45 scending toward the surface of the leather and being moved outwardly thus drawing the second thread in the form of a loop through the loop of needle thread, the movement of the thread-catcher being automatically 50 regulated to the thickness of the leather. The loop of second thread having been drawn through the loop of needle thread, the take-up commences to draw on and pull the loop of needle thread back 55 and into the leather for a given distance,

that having been previously determined by adjustment made by the operator, and, during this operation, the loop of needle thread pulling on the loop of second thread doubles and draws the latter into the leather, 60 thereby thoroughly filling the hole made by the needle, and during this operation the thread-catcher remains in engagement with the loop of second thread, said catcher gradually giving up, and finally discharging 65 the loop of second thread into the hole in the leather.

One part of my invention consists in a sewing machine containing a work-support, a looper located below the work-support 70 and adapted to engage and measure off the thread to be taken by the needle, a hooked needle located above the work-support and adapted to engage the said measured thread and draw the same into and above the material to form a loop above the same, and a thread guide located above the material close to one side of the loop of thread, yet held by the said needle, and carrying a second thread, combined with a thread-catcher, 75 and means to move it to cause said thread-catcher to enter the loop held above the material by the needle, engage at the opposite side of the said loop the thread presented by the said thread-guide, and pull it through 85 the loop of needle thread at the upper side of the said material, substantially as will be described.

Other features of the invention will be hereinafter more fully described and pointed out in the claims.

Figure 1 is a front elevation of a sewing machine embodying my invention, the parts being in position to commence work, the foot being elevated from the work-support 95 as it would be with a piece of leather under it. Fig. 2 is a right-hand side elevation of the machine, the fast and loose pulleys being omitted. Fig. 2^a, a detail of the tension device for the needle thread. Fig. 3 is a 100 section looking to the right of the dotted line α , Fig. 1. Fig. 4 shows the needle enlarged. Fig. 5 is a detail showing part of the mechanism instrumental in stopping the forward or inactive throw of the pull-off 105 device coöperating with the needle thread. Fig. 6 shows several different views of the acting end of the thread-catcher. Figs. 7 to 12 show different positions of the stitch-forming parts in the making of a stitch. 110

Fig. 13 shows the stitch; Fig. 14 shows the feed frame detached. Fig. 15, the awl and needle segments side by side, but removed from their support.

5 The frame-work consists essentially of a suitable column A on which is a head A' of suitable shape to contain the working parts.

10 The feed-frame A² see Fig. 14, is fastened to a rod A³ fitted to slide in bearings in the head, one end of the rod having co-operating with it a feed-regulating device A⁴, shown in Fig. 1, as an adjustable stop, a spring A⁵ acting against the other end of the rod to press the rod to the stop 15 and hold the roller or other stud A⁶ of the said frame pressed toward the side cam A⁷ of the cam hub A⁸ fast on the main shaft A⁹ of the machine, the stop permitting more or less of the full stroke of the cam to be 20 utilized for the length of the feed as required for the work to be done, parts of the groove in the said hub being wider than the roll. The feed-frame has at its rear end a projection A¹⁰ which enters and slides in 25 a guide-way A¹² made in the head, and the front of the head has projecting ears which carry a stud A¹³, on which are mounted to be oscillated both the awl segment a and the needle segment b, the former carrying 30 the awl a', and the latter the needle b', shown enlarged in Fig. 4, the needle segment being mounted on a sleeve a^x of the awl segment the needle for a short distance from its hook being of one diameter, as at 35 1, Fig. 4, and then it is of a larger diameter, as at 2, to further enlarge one part of the hole previously made by the point of the awl, thus making a hole of two diameters, one of which is to receive two thicknesses 40 of needle thread o, while the larger part of the hole is to receive four thicknesses of second thread t, the shank 3 of the needle being shown as of yet greater diameter.

The awl segment is actuated to enter the 45 material by a segment lever a⁹, pivoted on a rod a^{3x}, moved by suitable cam groove a⁴, see dotted lines Fig. 2, at the inner or left side of the cam hub B, and the needle segment is moved by a segment lever b⁹ mounted on rod a^{3x} at the left of the awl lever, and actuated by the cam groove b⁴, shown by dotted lines Fig. 3, of the cam hub A⁸ on shaft A⁹.

The movement of the awl and needle into 55 and from the work will be hereinafter described, and the lateral or feeding movement of the awl while in the work is derived from the feed frame.

The feed-frame carries a thread-presenter, 60 composed essentially of a finger c, having a substantially vertical notch with projecting side edges, shown best in Figs. 8 to 12, fixed to a hollow slide bar c' see Figs. 2 and 3, mounted, as herein shown, in a guide-way in the feed-frame, the said bar having

a series of teeth at c² which are engaged by the teeth of a segment lever c³ having a roller or other stud c⁴ which is acted upon by the peripheral cam c⁵ on the cam hub A⁸, the projections at the face of the finger acting to receive across them a part of the needle thread then drawn aside by a looper d which acts on the said needle thread o between the last stitch and the thread guide d' forming preferably part of the work-support d², and located at a short distance from the under side thereof, the presenter being moved at times toward the needle to engage the needle thread at a distance from the needle thread guide and bend it across 75 the needle, so that the hook of the needle, as the needle rises, will unerringly catch the thread and draw it through the material, a spring e^x adjusted by a screw e^{xx} in a hub forming part of a segment lever c³, 80 pressing the roll c⁴ against the cam c⁵.

The looper d which pulls the needle thread for a like distance at each rise, takes its thread from a portion of thread previously pulled off from the thread supply and 85 then held ready to be given up to the looper. The looper has at its inner end a suitable hook 4, see Fig. 8, the shank of the looper being connected to an arm d¹⁹ of a lever d^{2x} having a roller or other stud d⁸ entering 90 the cam groove d⁴ of the cam hub B.

The presser-foot e which bears on the material on the work-support is of the kind adapted to be raised a uniform distance from the work whatever its thickness to 100 permit the awl to feed the same over the work-support. The presser-foot e is attached to a curved bar e' adapted to slide on or in a circular race or track e², the center of which is eccentric with the center of motion of the awl and needle, a hole in the race or track exposing teeth, see Fig. 3, to be engaged by the presser-foot lifting lever e³ clamped to the rock-shaft e⁴, the rear end of said lever having a series of ratchet teeth e⁷, which, at some point, is engaged by the lifting pawl e⁹ carried by a lever e⁸ provided with a roller or other stud entering a groove e⁸ in the outer or right hand side of the cam B, the lever e³ being acted on by the 105 torsional spring e^{xx}, regulated by a collar e^{xx}, thus depressing the presser-foot with a spring pressure on the material. The cam f⁵ connected to the end of lever e³ acts as a rest to insure the withdrawal of the pawl 110 from the ratchet teeth when the said pawl arrives in its backward or starting position.

The thread pull-off f having a roll f' over which passes the needle thread is made as 115 a lever pivoted on the rock-shaft e⁴, the hub b⁸ of the lever having a toe 5 which is acted upon by a toe 6 on the hub of the lever b⁸ used to move the needle segment, said toe 6 meeting the toe 5 and moving the pull-off 120 6 away from the two brake studs 7, 8, when 130.

the needle is being inserted, and at a time when the clamp 9 is acting to hold the needle-thread between it and the stud 8, thus drawing from the usual wax-pot and tension device, not shown, the needle-thread, enough for the next stitch. The thread pull-off is moved by spring f^2 toward and between the brake studs to give up the slack thread pulled from the wax-pot, after which the brake 10 acts to hold the thread while the take-up g , to be described, acts the brake 9 being loose when the take-up is acting.

The rear end of the pull-off lever has an arm 12 provided preferably with an adjusting device, shown as a screw 13, which acts on the arm f , see Figs. 3 and 5, of a rocking lever f^4 , the upper end of which, as shown in Fig. 3, bears on a cam track f^5 attached by a screw f^6 to the rear end of the lever e^8 at one side of the ratchet teeth thereof, the lever being acted upon by a spring f^8 , see Fig. 2, which keeps it on the cam, and the position of the cam f^5 being dependent on the thickness of the material under the presser-foot, and the cam f^5 will consequently stop the lever f^4 and arm f^3 in a position variable with the thickness of the material, and sooner or later stop the forward movement of the pull-off lever between the studs 7 and 8 to accord with the material.

The take-up lever g has at its upper end a roller or other stud g^8 which enters a cam groove g^7 in hub A^8 , and the lever carries at its lower end a stud or roll g' over which the needle-thread passes, and between it and the material the needle-thread is acted upon by a slack thread controller made as a lever g^2 having a roller g^3 , pivoted concentric to the roll g' , a spring g^4 acting to keep the roll on the thread, and as the take-up completes its active or drawing stroke, the rear end of the lever g^2 may, by the adjustment of the regulator g^5 by the threaded nut g^6 , be made to strike sooner or later the said regulator and be actuated by its cam surface to more or less bend the needle-thread and aid in putting a little extra strain or tension on the thread to better adapt the take-up to setting the stitch at the right tension on the surface of the leather.

The thread catcher i' , in this present embodiment of my invention has a hook or finger i to engage a second thread t supplied close to the rear side of the then open loop of needle-thread by a stationary thread guide t' , and a cast-off bridge i^2 having at one side of it a space i^3 for the entrance therein of the hooked needle, and a heel i^4 to prevent the loop of needle-thread cast-off the needle from slipping too far outwardly as the catcher descends.

The machine frame has mounted upon it at i^9 Fig. 3, a lever i^8 , having at one end a

sleeve i^7 , and said lever has a roller or other stud i^{10} at one end, which is acted upon by a cam i^{12} of the hub A^8 , said roll being kept pressed toward said cam by a spring i^{13} , resting at one end on a collar of a rod i^{13x} , the upper end of the rod entering a hole in a stand i^{14} the upper end of the spring resting against said stand. The sleeve i^7 has connected to it a leg 16 provided with a roller 17. The sleeve i^7 receives in it loosely a rock-shaft i^6 , having connected to or forming part of it the thread catcher lever i' , carrying the thread catcher i' to be described. The upper end of the lever i' has a roller or other stud i^{15} which by a spring i^{16} is kept pressed toward a cam i^{15x} . The opposite end of the rock-shaft i^6 has clamped firmly on it an arm 19 having a roll 18. The segment bar e' has attached to it and movable with it two cams m , n , for cheapness of construction made in one piece, the cam m serving to arrest by its surface the roller 17 and the cam n the roller 18. The cam i^{15x} turns the lever i' to move the thread catcher i' toward and through the loop of needle-thread held by the hooked needle to enable the catcher to engage the second thread t , standing between the stops and the stationary thread guide t' .

The cam i^{12} acts on the roll i^{10} to lift the sleeve and with it the lever i' , and at the same time the cam i^{15x} acting on the lever i' causes the rising thread catcher to enter the open loop of the needle-thread close to the point where it is engaged by the hook of the needle, and to pass through said loop far enough to engage the second thread t coming from the stationary thread-guide t' and going to the work.

The thread-catcher having engaged the second thread the cam i^{12} returns and permits the spring i^{13} to depress the sleeve i^7 and as the sleeve descends the roll 18 meets the cam n and stops the outward movement of the thread-catcher produced by the spring i^{16} , and the roll 17 meets the cam m and stops the descent of the thread-catcher, the said cams n and m occupying different positions during the stitching that depending on the thickness of the stock on which the presser foot e rests, the said stock varying in thickness.

The cam i^{15x} is of such shape that the loop of second thread having been measured or drawn outwardly through the loop of needle-thread, it will positively move said thread-catcher toward the line of stitching and the path of movement of the needle to thus enable the said thread-catcher to give up to the loop of needle thread, at the proper speed and time, the loop held by it to be drawn by the needle-thread into the stock, as will be described. The extent of outward movement of the thread-catcher

and the length of the loop of second thread drawn out through the loop of needle-thread is thus regulated automatically by the thickness of the material under the presser-foot.

5 As the leather increases in thickness the thread-catcher descends less and less measuring the loop of second thread principally by its height from the surface of the work; the hook *i*, however, moves slightly 10 to the front to clear the needle and in so much assists in measuring said loop. The hook *i* in its descent should remain high enough to clear the channel-flap and the said hook begins to move further to the 15 front, governed by the cam *m* and performs, when the work is quite thick, the principal portion of the measuring function.

The brake 10 to act on the needle thread between the pull-off and the usual wax-pot 20 or tension device, not shown, but of usual construction as represented in my patent No. 545,184, dated Sept. 3, 1895, is shown as a lever attached to a rock-shaft *h* having an arm *h'* provided at its upper end with a 25 roller or other stud *h''* which is acted upon by a peripheral cam *h³* on the cam hub *B*, and the clamp 9 to act on the needle-thread between the take-up and the needle is shown as a lever fast on a rock-shaft *h⁴*, the rock-shaft having an attached arm *h⁵* provided 30 at its upper end with a roller or other stud *h⁶* which is acted on by a peripheral cam *h⁷* on the hub *B*, the said clamps being so timed as to their operation that one or the other 35 of them always holds the needle-thread, and there is consequently no time at which any but the exact part of the needle-thread to be used can be acted upon and disturbed.

The thread *t* is acted upon by a tension 40 device *o²*, shown in Figs. 2 and 2^a as a pivoted lever normally held against the said thread by a spring *o³*, adjustable by a screw or equivalent device *o⁴*.

The rod *m'* connected in practice with a 45 suitable treadle at the floor, is, when lifted, made to turn the lever *m²* pivoted at *d^{3x}* and having at its upper end a toothed block *m³* engaging the teeth of an internally-threaded collar *m⁴* mounted on a hollow projection or 50 sleeve *m⁶⁰*, connected to the frame-work *A'* and having at its outer side numerous steep threads *m⁶¹*, the rotation of the collar on the fixed sleeve causing the said collar to be moved on said sleeve longitudinally with relation to the shaft *A⁹*, causing the end of the collar to bear against a washer *m⁶²* lying 55 against the hub of the loose pulley *m⁵* causing the conical face thereof to be pressed firmly against the conical face of the fast pulley *m⁶* secured on the main shaft to start 60 the machine. When the treadle is released a spring *26* moves the lever *m²* in the opposite direction to stop the machine, and an extension 21 of the lever *m²* meets the lever

23 on the rock-shaft *h* and lifts the brake 65 10 from the needle-thread, thus leaving the thread free to enable the shoe to be pulled out from between the foot and work-support.

A roll 100 on an eccentric stud 22 in the front end of extension *m⁷*, of lever *m²*, by 70 engaging the cam 25 on the fast pulley *m³* is held out, and holding the lever *m²* in such position that when the treadle is released the spring *26* cannot act to disconnect the loose from the fast pulley to stop the machine except at that part of the revolution of the cam shaft when the clamp 9 is lifted to free the needle-thread on the brake-stud 75.

7. The rod *m²⁰* is connected to an arm *m²¹* loose on the shaft *e¹* along-side of an arm *m²²* fixed to said shaft, and having its outer end overlapping the arm *m²¹*. The arm *m²²*, by or through the spring *e^{xx}* and shaft *e¹*, is held normally against the arm *m²¹*, but to lift the presser-foot, the operator, by 85 a suitable treadle connected to said rod *m²⁰*, will raise it thus moving the shaft and the lever *e³*.

Viewing Figs. 7 to 12, I will describe the operation of the machine. Let it be supposed that the material *w* has been put in place between the work-support and the foot *e*, and thus the looper *d* beneath and in rear of work-support *d²* has been moved to pull to the left from thread-guide *d'*, in said support, a fixed quantity of thread and holds it distended clear of the awl and needle-barb. Now the awl *a'* goes up through the work from beneath and near the end of its stroke the presser *e* is slightly raised, and 100 the awl completes its ascent lifting slightly the material from the work-support *d²* to thus ease the feeding movement, the awl *a'* moves to the left to feed, the presser-foot *e* goes down while the awl is up, and at the 105 end of this movement the clamp 10 is raised to unlock the thread on the roll 7, and the awl *a'* goes down and at the same time the needle *b'* goes down, and moved by it, the pull-off *f* draws thread from the wax-pot. 110 The thread presenter *c* having at its front end two ribs with a groove then comes forward under support *d²* and engages that half of the loop of thread held distended by thread-arm *d*, from the thread-guide *d'*, and 115 lays it into the barb of needle *b'*, and the clamp 10 is caused to descend on the needle thread lying on the roll 7, lock the thread behind the pull-off, and the clamp 9 is opened just before the needle rises. Now as 120 the needle *b'* rises with the loop of thread, the pull-off *f* is released by the rising of the projection 6, so that the spring *f²* is free to act and leave its thread slack, and the looper *d'* then moves toward the needle 125 yielding its thread to the needle, but it does not release it, and the take-up *g'* also rises and yields its thread to the needle.

The thread-catcher i' goes to the rear between the strands of the needle-loop and into position to engage the second thread and rises a little to strip the needle-loop from the needle-barb see Fig. 9, the barb having gone down a little while thread-catcher i' rises. The thread-catcher i' then goes down, the needle-loop being held down loosely upon it by the auxiliary take-up g^3 , and engages and deflects the second thread, Fig. 10, then extending from the last stitch on the left up to the fixed thread-guide t' on the right. The thread-catcher i' then comes forward measuring and drawing the loop of second thread through the needle-loop, and holding it while it is drawn down hard upon the work, and then goes back to release said loop while it is being drawn down into the work, after which it rises to its initial position. The take-up g' is then moved to draw down the needle-loop and with it the loop of second thread to the top of the work, and still descending (the loop of second thread having been released) draws and doubles said loop into the work and completes the stitch. During the latter part of this movement the looper d , which has remained in the position, above described, toward the needle is moved into its initial position in readiness to reengage the standing side of the next needle-loop to be made, releasing the thread as it goes, the take-up g' , as it finishes its down stroke, causing the tail g^2 of the auxiliary take-up g^3 to strike the adjustable cam g^5 , thus giving a quick jerk to the needle-thread thereby taking up the slack and firmly setting the stitch, and then the looper d is moved again, as first described, to pull from the thread-guide d' the fixed quantity of thread and hold it for the next stitch.

The brakes 9 and 10 referred to are each actuated independently of the other, so that the brake 9 clamps the needle-thread between the pull-off and the take-up when the pull-off is being actuated to pull off thread from the thread supply, and thereafter, when the take-up is being actuated to take up the loop of needle-thread, the brake 10 between the pull-off and thread supply is closed to act on the needle thread, one or the other of said brakes always operating to hold the needle-thread fast, so that at no time can the needle-thread slip and be given up to the needle except in exactly the proper and established quantity.

The loop of second thread t may be drawn out more or less according to the length desired for it, and it may be pulled wholly or partially in the hole 23, and the end of the loop of second thread may be left in the channel and be battered over to aid in clinching the thread as the wax hardens, if desired.

Having described my invention, what I

claim and desire to secure by Letters Patent, is:—

1. In a sewing machine, a work-support, a looper located below the work-support and adapted to engage and measure off the thread to be taken by the needle, a hooked needle located above the work-support and adapted to engage the said measured thread and draw the same into and above the material to form a loop above the same, and a thread guide located above the material close to one side of the loop of thread yet held by the said needle, said thread guide carrying a second thread, combined with a thread-catcher, and means to move it to cause said thread-catcher to enter the loop held above the material by the needle, engage at the opposite side of the said loop the thread presented by the said thread guide, and pull it through the loop of needle thread at the upper side of the said material, substantially as described. 70

2. In a sewing machine, a work-support, a guide for the needle-thread, a pull-off, means to move it to act on said thread between the needle-thread-guide and the thread supply, a looper located below said work-support, means to move the same to engage the needle-thread between the said needle-thread guide and the work, means to move said looper to measure off the needle thread for a stitch, a hooked needle, means to actuate it to engage the measured thread held by the looper and draw the said thread up through the material for a stitch, a thread-guide located above the material close to said loop of needle-thread and presenting a second thread, and a thread-catcher, and means to move it, whereby said thread-catcher is made to enter said loop of needle thread, and take the second thread from the thread-guide also above the material and draw it therefrom through the loop of needle-thread yet held by the said needle above the material, and gradually give up said thread to the strain of the loop of needle-thread as then the latter is being taken up, combined with a take-up to act on and take up the loop of needle-thread, substantially as described. 95

3. A sewing machine comprehending the following instrumentalities, viz:—a work-support, a hooked needle to seize a needle thread below the material, and draw it above the material to form a loop therein, a thread-guide located above the material and presenting a second thread, a thread-catcher located above the material and adapted to enter the loop of needle-thread held by said needle and engage at its opposite side a second thread presented by said thread guide, means to regulate the descent, toward the material, of the thread-catcher in engagement with the said second thread, and means to impart to said thread-catcher 110

115

120

125

130

- a variable outward movement, whereby the loop of second thread is varied in length according to the thickness of the material, substantially as set forth.
5. 4. In a sewing machine, a hooked needle, a pull-off for the needle-thread, a take-up for said thread, a brake for the needle-thread between the said pull-off and thread-supply, an independent brake for said needle-thread between said pull-off and said take-up, and means to actuate said pull-off and take-up, combined with means to actuate said two brakes independently, whereby when the pull-off works to pull off thread from the 15 thread-supply, one of the said brakes acts on the thread between the pull-off and the take-up, the other of the said brakes is removed from the thread, and when the take-up acts to take up the loop of needle thread, the brake located between the pull-off and the thread-supply acts to hold the thread, while the brake located between the pull-off and the take-up is opened, one or the other of said brakes always operating to hold the 25 needle-thread, substantially as described.
5. In a machine for stitching with two threads, a needle, means to actuate it to penetrate the material and leave in the material a loop of needle thread, a thread catcher having a prong and a heel, means to present a second thread to lock the loops of needle thread, and means to actuate said thread catcher to cause its prong to pass through the loop of needle-thread and take said second thread from the means presenting it, the heel of said loop catcher acting to keep the loop of needle thread in position during the movement of the said catcher through the loop to engage said second thread and means 35 for drawing the loop of needle thread into the material, substantially as described.
6. In a machine for stitching with two threads, a hooked needle, a looper to draw and measure the thread to be taken by said 45 needle, means to actuate said needle to draw a loop of thread through the material, a guide located above the material to present a second thread, and a thread-catcher, combined with devices to move said thread-catcher and cause it to enter the loop of needle thread, engage said second thread, draw it through the loop of needle thread, and with devices to limit the outward movement of said thread-catcher according to the 55 thickness of the material under the presser-foot, substantially as described.
7. In a sewing machine, the following instrumentalities, viz:—a looper to engage the needle-thread and draw the same from the 60 thread-guide preparatory to the action of the needle, a thread-presenter to put the thread onto the needle, a needle to form a loop of needle-thread, a thread-guide for a second thread, a thread-catcher to enter the loop of needle-thread and engage said second thread, means to regulate the descent toward the material of the thread-catcher in engagement with the second thread, and means to impart to said thread-catcher a variable movement according to the thickness of the material while said catcher acts to form the loop in the second thread, substantially as described.
8. In a machine for stitching with two threads, a work-support, a hooked needle located above said work-support, means to operate said needle and cause it to pass through the material on the work-support, engage and draw a loop of needle thread from below said work-support to the surface 80 of the material, a thread guide located above the material and presenting a second thread, a thread-catcher, its carrying lever, and means acting on said carrying lever to raise it and cause the thread-catcher to enter the 85 loop of needle-thread, engage the said second thread, and draw it through the loop of needle-thread for a variable distance according to the thickness of the material, and devices to limit the descent of the thread-catcher toward the material according to the thickness thereof, substantially as described.
9. In a sewing machine, a presser-foot, a hooked needle, a pull-off, and means to move the pull-off always to a predetermined point 95 when pulling off thread from the thread supply, combined with a regulating device, and a cam controlled as to its position by the thickness of the material under the presser-foot, the said regulating device by its varying position regulating the return stroke of the pull-off when giving up the thread, thus adapting the pull-off to coöperate with material of different thickness, substantially as described.
10. In a sewing machine, a hooked needle, and a looper to engage the needle-thread and draw and measure the same preparatory to presenting said thread to the needle, combined with a feeding frame, and a thread-presenter, and means to move the thread-presenter in the said frame to coöperate with the needle, substantially as described.
11. In a sewing machine, a segmental toothed bar, a curved guide-way in which 115 said bar slides, a presser-foot attached to one end of said bar, a lever toothed at one end to engage the teeth of said bar, and having at its other end ratchet teeth, combined with a pawl, means to move it uniformly, 120 and a rest for one end of said pawl when in its retracted position, said pawl in its operation engaging one or another of said ratchet teeth according to the thickness of the work on which the presser-foot rests, substantially as described.
12. In a sewing machine the following instrumentalities, viz:—a presser-foot, a seg-

mental bar to which it is connected, a work-support, a pull-off, and devices to actuate the said segmental bar to lift the presser-foot, said devices having a cam and a regulator acted upon by said cam, and devices to operate said pull-off, substantially as described, whereby the starting point of the pull-off may be regulated according to the thickness of the material, substantially as described.

13. In a sewing machine, the following instrumentalities, *viz*—a work-support, a hooked needle, a thread presenter, a clamp to clamp the needle thread, and a take-up, combined with a spring actuated slack thread controller composed of a lever having at one end a sheave and pivotally mounted on said take-up lever and acting upon the needle thread between the take-up lever and the needle, substantially as described.

14. In a sewing machine the following instrumentalities, *viz*—a work-support, a hooked needle, a thread presenter and a take-up lever, combined with a slack thread controller composed of a lever having at one end a sheave pivotally mounted upon said lever and acting upon the needle thread between the take-up lever and the needle, and a device to govern the extent of the movement of said slack thread controller for the purposes set forth.

15. In a sewing machine, the following instrumentalities, *viz*—a presser-foot, a curved frame connected therewith; a work-support; a pull-off; and devices to actuate the said curved frame to lift the presser-foot, the said devices having a cam and a regulator acted upon by the said cam and between it and the pull-off to operate substantially as described, whereby the starting point of the pull-off may be regulated according to the thickness of the material, a locking device to hold the thread between the take-up and the thread supply, an independently actuated locking device to hold the thread between the pull-off and thread take-up, and means to actuate the take-up, to operate, substantially as described.

16. In a wax thread sewing machine, a hooked needle, a thread-measuring device to measure off the thread to be drawn by the needle in loop form through the stock, a thread-catcher having a hook, a heel and a cast-off bridge to enter the loop of needle thread and engage a second thread, and means to draw and measure the latter thread in loop form through said loop of needle thread according to variations in thickness of stock being sewed, substantially as described.

17. In a sewing machine, a pull-off, having a projection 5, a spring to move the pull-off to give up the thread pulled off by it, combined with the needle segment and its actuating lever having a projection 6 to act

on the projection 5 to actuate the pull-off positively, substantially as described.

18. In a sewing machine, a hooked needle, means to actuate it, a take-up, means to actuate it, the studs 7 and 8 to support the needle-thread, a pull-off having a roll bearing on said thread between said studs, means to actuate said pull-off, the clamps 10 and 9 connected respectively with rock-shafts h and h' , combined with means to move said rock-shafts whereby the shaft h is moved to cause the clamp 9 to hold the needle thread, and the shaft h' is moved to cause the clamp 10 to release the said needle-thread when the pull-off is acting to pull off thread from the thread supply, means for actuating said rock-shafts, causing the clamp 10 to act on and hold the needle-thread, and the clamp 9 to release said needle-thread when the take-up acts, substantially as described.

19. In a sewing machine, a work-support, a hooked needle to engage a needle-thread below said work-support and draw it above the material in the form of a loop, a stationary thread-guide for a second thread, said thread-guide being located above the material close to where the loop of needle-thread is held by the said needle, combined with a thread-catcher, its carrying lever d^1 , a rock shaft to which said carrying lever is connected, a lever having a sleeve to receive said rock-shaft, a cam to move the latter lever to raise and lower the thread-catcher, and a second cam to act on said carrying lever to vibrate it and the said thread-catcher, substantially as described.

20. In a sewing machine, the combination with a hooked needle and means for actuating the same to draw a loop of thread through the work, of a thread-catcher located on the same side of the work as the needle, arranged to enter a loop of needle thread, engage a second thread and draw a loop thereof through the loop of needle thread, and means for actuating the thread-catcher to draw loops of second thread varying in length with the thickness of the material, substantially as described.

21. In a sewing machine, the combination with a hooked needle and means for actuating the same to draw a loop of thread through the work, of a thread-catcher located on the same side of the work as the needle, and means for actuating the thread-catcher to cast off the loop of needle thread from the needle, engage a second thread and draw a loop thereof through the loop of needle thread, substantially as described.

22. In a sewing machine, the combination with a hooked needle and means for actuating the same to draw a loop of thread through the work, and means acting on the needle side of the work to place a loop of second thread through a loop of needle thread, and means for varying the length

- of the loop of second thread according to the thickness of the material, substantially as described.
23. In a sewing machine, the combination with a hooked needle and means for actuating the same to draw a loop of thread through the work, of a thread-catcher located on the same side of the work as the needle, means for actuating the thread-catcher to cause it to place a loop of second thread through a loop of the needle thread, a take-up to act on the needle thread and means for actuating the thread-catcher to hold and then release the loop of second thread during the action of the take-up, substantially as described.
24. The combination with stitch forming mechanism of a thread measuring mechanism including thread supports, a movable thread engaging device intermediate said supports and movable across the line of the thread between said supports, means for moving said thread engaging device toward and away from the thread between said supports and across the line of said thread, and an adjustable stop in the path of movement of said thread engaging device as it moves away from said thread; substantially as described.
25. The combination with stitch forming mechanism of a thread measuring mechanism including the combination with a plurality of thread-clamps, of actuating mechanism therefor, means whereby in the operation of said mechanism the thread is at all times engaged by one or the other of said clamps, and means under the control of the operator for throwing a clamp into open position; substantially as described.
26. In a sewing machine, the combination with stitch forming devices of a main take-up, a spring actuated auxiliary take-up or slack thread controller, and means for positively actuating the auxiliary take-up to increase the strain put upon the thread by the main take-up; substantially as described.
27. In a sewing machine, the combination with stitch forming devices of a main take-up, a take-up lever, an auxiliary take-up mounted upon the take-up lever and means for positively actuating the auxiliary take-up to increase the strain put upon the thread by the main take-up; substantially as described.
28. In a sewing machine, the combination with stitch forming devices of a take-up, a pull-off, two thread clamps engaging the thread respectively between the supply and the pull-off and between the pull-off and the take-up, means for actuating said clamps to intermittently clamp and release the thread and to cause the thread to be engaged at all times by one or the other of said clamps, and means under the control of the operator for actuating one of said clamps to release the thread while the stitch forming mechanism is at rest.
29. In a sewing machine, the combination with stitch forming devices of a take-up, a pull-off, two thread clamps engaging the thread respectively between the supply and the pull-off and between the pull-off and the take-up, means for actuating said clamps to intermittently clamp and release the thread and to cause the thread to be engaged at all times by one or the other of said clamps, and means under the control of the operator for stopping the machine with one of said clamps in open position and for moving the other clamp to open position; substantially as described.

In testimony whereof, I have signed my name to this specification, in the presence of two subscribing witnesses.

LOUIS GODDU.

Witnesses:

H. P. FAIRFIELD,
A. VAN WAGMEN.

Corrections in Letters Patent No. 1,106,800.

It is hereby certified that in Letters Patent No. 1,106,800, granted August 11, 1914, upon the application of Louis Goddu, of Winchester, Massachusetts, for an improvement in "Sewing-Machines," errors appear in the printed specification requiring correction as follows: Page 3, line 17, for the reference-letter "f" read *f³*; page 4, line 115, for the compound word "thread-arm" read *loop*; page 5, line 126, strike out the word "second"; and that the said Letters Patent should be read with these corrections therein that the same may conform to the record of the case in the Patent Office.

Signed and sealed this 6th day of October, A. D., 1914.

[SEAL.]

R. F. WHITEHEAD,
Acting Commissioner of Patents.
